UNITED STATES PATENT OFFICE.

CYRUS S. RADFORD, OF PHILADELPHIA, PENNSYLVANIA.

LOCK MECHANISM.

1,070,178.

Specification of Letters Patent.

Patented Aug. 12, 1913.

Application filed May 19, 1909. Serial No. 496,941.

To all whom it may concern:

Be it known that I, CYRUS S. RADFORD, a citizen of the United States, and resident of the city and county of Philadelphia, State of Pennsylvania, have invented an Improvement in Lock Mechanism, of which the following is a specification.

It is one of the objects of my invention to provide a simple and efficient mechanism to enable a lock to be operated by a key inserted through the knob of a door or drawer. For this purpose I employ a tubular sleeve which is inserted through the lock casing and knob, and contains a key actuated part, adapted to be operated by a key inserted through the knob and sleeve, and to control the operation of the lock-bolt. This sleeve with its key-actuated part may be readily applied to ordinary locks. The portion of the sleeve which extends through the lock casing is slotted, and the key actuated part within the sleeve operates the devices for actuating the bolt or controlling its operation through this slot. By extending the front end of the sleeve beyond the face of the door or drawer to form a bearing for the knob and mounting the knob loosely upon it, I enable the knob to be used to actuate a spring latch.

In the drawings, Figure 1 is a front elevation of a lock embodying the invention and showing the same applied to an ordinary handle or knob; Fig. 2 is a front elevation of the same with the face plate of the lock casing and handle removed and the spindle-socket in vertical section; Fig. 3 is a vertical section on the line A—A of Fig. 1; Fig. 4 is a plan view of the key; Fig. 5 is a front elevation similar to Fig. 2 but showing the invention applied to a spring latch and its actuating knob; Fig. 6 is a vertical sectional view of the lock and latch on the line B—B of that figure but including the face plate and latch actuating knob; Fig. 7 is an elevation similar to Fig. 2 but showing a modification; Fig. 8 is a vertical section of the lock shown in Fig. 7 on the line C—C of that figure but including the face plate and knob; Fig. 9 is a plan view with part in section of the key for actuating the lock shown in Figs. 7 and 8; Fig. 10 is a front elevation similar to Fig. 7 but showing the modified form of locking mechanism of Figs. 7 and 8 applied to a spring latch; Fig. 11 is a vertical sectional view of

the modification shown in Fig. 10 on the line D—D of that figure but showing the same with knobs adapted to be actuated from either side; Fig. 12 is a longitudinal section of the knob, sleeve and spindle with an additional key socket; Fig. 13 is a transverse section of the same on the line E—E of Fig. 12; and Figs. 14, 15 and 16 are front elevations similar to Figs. 2, 5, 7 and 10 illustrating further modifications.

a is the lock-case which contains the bolt, latch and actuating mechanism and is adapted to be secured to the frame of a door, lid or drawer in the usual manner. I shall first describe the construction shown in Figs. 1—3, in which the lock has an ordinary bolt *b* and is applied to a door or drawer provided with a knob or handle *c*. The bolt *b* is actuated by the bit *d* of a key-pin *e*, which is journaled in a sleeve *f* extending through the knob and lock-casing. This sleeve *f* is cut away or slotted at the lower portion of the inner end as at *f'* and projects through slots in the face plate *a'* and case *a*. It is secured in place by a nut *f''* on its threaded extremity. The key-pin *e* is journaled at its rear-end in the case *a* and the bit *d* projects through the slot *f'* into actuating engagement with the bolt *b*. The front end of the key-pin is suitably notched as at *e'* to engage the end of a key *g* inserted through the sleeve in the knob. The key-pin may thus be actuated by the key *g* to operate the bolt, the slot *f'* in the sleeve *f* being sufficiently wide for the purpose, preferably 90°. In this construction an ordinary knob or handle is employed, but in Figs. 5 and 6 I have shown the knob arranged for actuating a spring-catch *h* which is operated by a pin *h'* on the knob extending through a slot in the face plate and engaging a slot in the catch. In both of these forms the key *g* engages directly with the key-pin *e* which actuates the bolt, but in the forms shown in Figs. 7—11 I employ intermediate devices—preferably gears—for transmitting motion from the key to the key-pin and its bit.

i is a short spindle journaled in the lock case *a* and projecting at the front through the face plate *a'* into the tubular knob *c*. This spindle is arranged within the tubular sleeve *f*, and carries a small pinion *j*, the teeth of which engage the teeth of a small segmental gear *k* on the key-pin *e*, which is journaled on the lock case immediately be-

low the spindle *i*, so that the teeth of the pinion and gear will engage through the slot *f'* in the sleeve *f*.

m m are small springs secured to the gear *k* and embracing the outside of the sleeve *k* for the purpose of preventing the key-pin turning so far as to entirely disengage the teeth of the gear *k* from the pinion *j*. The spindle *i* may be operated by a suitable key 5 *g'* (Fig. 9) inserted through the knob *c* and having a socket *g²* to engage the head of the spindle. In the form shown in Fig. 8 the knob *c* is integral with the sleeve *f*. This form is particularly adapted for small 10 metal knobs, and the spindle *i* permits a very small key to be used.

In Figs. 10 and 11 the construction is shown applied to a double knob adapted to be operated from either side and also connected with a spring latch. In this form 20 the outer end of the sleeve *f* is connected with a second sleeve *f²* on which the knob *c'* is mounted and the rear end of the spindle *i* is extended through the lock casing into this 25 sleeve *f²* as shown at *i'*. The two knobs are connected by a pin *h²* which actuates the spring catch *h* in the usual manner.

In all of the forms shown the key inserted through the knob engages directly 30 with the key-pin or spindle *i*. This does not permit of much variation in the keys. If desired, however, a set of tumblers or an auxiliary key sleeve may be employed in the sleeve *f*, through which the key must 35 pass to operate the key-pin or spindle *i*. Such construction is shown in Figs. 12 and 13, in which *n* is a rotary sleeve in the sleeve *f* in front of the spindle *i*, having an irregular passageway *n'* through which the 40 key must pass before its end can engage the spindle.

In each of the forms shown in Figs. 1-11 the key-pin actuates a simple bolt and may be applied to an ordinary lock. In the construction shown in Fig. 14, however, a special locking bolt and actuating devices are employed. The spindle *i* is provided with the pinion *j*, as in the forms shown in Figs. 7-11, but it engages a segmental gear *k'* on 45 a plate *o* pivoted in the lock case and having a cam slot *p* which engages a pin *p'* on the bolt *b'*. When the spindle *i* is turned by its key, the plate *o* will be rocked by the gears *j* and *k'* and the bolt *b'* will be projected or 50 retracted by the action of the cam slot *p* on the pin *p'*.

In the forms shown in Figs. 15 and 16, the key-pin *e* and its bit *d* act as a lock for a bolt *b²*, which is provided with a shoulder *s* or offset *s* engaged by the bit *d*. When the key-pin is operated to move its bit out of engagement with the shoulder *s* the bolt *b²* may be moved. In the form shown in Fig. 15 the bolt is projected by a spring *t* and 55 is retracted by a pin *h³* on the knob engag-

ing the bolt; in the form shown in Fig. 16 the bolt is both projected and retracted by a pin *h⁴* on the knob working between lugs *h⁵* on the bolt.

In the forms shown in Figs. 1-11 and 14 70 the bolt *b* or *b'* is actuated positively by power transmitting connections between the key-pin *e* or spindle *i*, while in the forms shown in Figs. 15 and 16 the bit *d* acts as a locking device to hold the bolt *b²* against movement until the bit is raised; in either case, however, the bit *d* and its connections 75 constitute motion controlling connections between a key actuated part—either the key-pin *e* or the spindle *i*—and the lock-bolt, by which the unlocking of the bolt is controlled by the operation of the key actuated part 80 operated by a key inserted through the knob and sleeve.

While I have shown the key bit *d* in Figs. 85 2, 5, 7 and 10 acting directly on a lock bolt it is apparent that it may operate through tumblers in the manner usual in ordinary tumbler locks. The bit *d* is similar to the bit of an ordinary key and may operate the lock-bolt in the same manner that an ordinary key operates, either directly or through tumblers or other connecting mechanism.

What I claim is as follows:

1. In a lock mechanism, the combination 95 with a lock casing and a drawer or door knob, of a tubular sleeve carried by the knob, projecting at its inner end through the back plate of the casing and provided with a slot, means to secure the projecting inner end of the sleeve against withdrawal through the back plate of the casing, a key actuated part in the sleeve, a lock-bolt, and motion controlling connections between the bolt and key actuated part working through the slotted portion of the sleeve.

2. In a lock mechanism, the combination 110 with a lock casing and a drawer or door knob, projecting at its inner end through the back plate of the casing and provided with a slot, a nut on the projecting end of said sleeve to secure it against withdrawal through the back-plate, a key actuated part 115 in the sleeve, a lock-bolt, and motion controlling connections between the bolt and key actuated part working through the slotted portion of the sleeve.

3. In a lock mechanism, the combination 120 with a lock casing and a drawer or door knob, the back plate of said casing being provided with a slot in line with the knob, a tubular sleeve having its outer end slotted extending through the knob and casing with 125 the extremity of the slotted end projecting through the slot in the back plate of the casing, a key actuated part in said sleeve adapted to be operated by a key inserted through the knob, a lock-bolt, and motion 130

controlling connections between the bolt and key actuated part working through the slotted portion of the sleeve.

4. In a lock mechanism, the combination with a lock casing, of a tubular sleeve extending entirely through the casing, a knob loosely mounted on said sleeve, a key actuated part within the sleeve journaled in the back plate of the casing and adapted to be operated by a key inserted through the knob and sleeve, a lock-bolt within the casing, power transmitting connections between the key actuated part and bolt, a latch, and operating connections between the knob and latch.

5. In a lock mechanism, the combination with a lock-casing, of a tubular sleeve extending entirely through said casing and having a slotted portion, a rotary spindle in said sleeve adapted to be operated by a key inserted through said sleeve, a pinion

carried by said spindle and working through the slotted portion of the sleeve, a lock-bolt in said casing, and power transmitting connections between said bolt and pinion. 25

6. The tubular sleeve *f* adapted to be inserted in a lock casing and having the slot *f'*, in combination with a rotary key actuated part journaled in said sleeve and provided with motion controlling means operating through said slot *f'* in the sleeve for controlling a lock, a knob loosely mounted on said sleeve in front of the lock casing, a spring latch, and a connection between said knob and latch. 30 35

In testimony of which invention, I have hereunto set my hand.

CYRUS S. RADFORD.
